(57) **CLAIM**

The ornamental design for an opacifying glass roof for an automobile, as shown and described.

DESCRIPTION

1. Opacifying glass roof for vehicle
    - 1.1 : Top view—roof windows not opacified
    - 1.2 : Top view—roof windows partially opacified at $\frac{1}{3}$
    - 1.3 : Top view—roof windows partially opacified at $\frac{2}{3}$
    - 1.4 : Top view—roof windows totally opacified
    - 1.5 : Bottom view—roof windows not opacified
    - 1.6 : Bottom view—roof windows partially opacified at $\frac{1}{3}$
    - 1.7 : Bottom view—roof windows partially opacified at $\frac{2}{3}$
    - 1.8 : Bottom view—roof windows totally opacified
- In the drawings, the broken lines in Figures depict portions of a vehicle that form no part of the claimed design.
